(57) **CLAIM**

The ornamental design for an anchor set tool, as shown and described.

DESCRIPTION

FIG. 1 is an upper perspective view of an anchor set tool showing my new design.

FIG. 2 is a top view of an anchor set tool showing my new design.

FIG. 3 is a left side view of an anchor set tool showing my new design.

FIG. 4 is a bottom view of an anchor set tool showing my new design.

FIG. 5 is a right side view of an anchor set tool showing my new design.

FIG. 6 is a first end view of an anchor set tool showing my new design; and,

FIG. 7 is a second end view of an anchor set tool showing my new design.

Any shading and cross-hatching are not features of the design but are utilized to illustrate the surface contours of the anchor set tool in the drawings.

1 Claim, 7 Drawing Sheets
